Term of patent 14 years

Int. Cl. D6—02

U.S. Cl. D15—3

FIG. 1 is a combined view in perspective of a chair and hair dryer showing my new design;

FIG. 2 is a combined front view of the chair and hair dryer of FIG. 1;

FIG. 3 is a combined side view of the chair and hair dryer of FIG. 1; and

FIG. 4 is a combined top view of the chair and hair dryer of FIG. 1.

The design is characterized by the combination of the circular armrest member and the bifurcated top in association with the hair dryer unit, all as best illustrated in FIGS. 1 and 3.

I claim:

The ornamental design for a combined chair and hair dryer, substantially as shown.
